FIRE ESCAPE

Léopold Fosty and Théophile Laurent, Bellevue,
Manitoba, and Frank Joseph Laurent, Find-
lay, Manitoba, Canada

Application June 11, 1936, Serial No. 84,654

4 Claims. (Cl. 254—153)

Our invention relates to fire escapes, more particularly having reference to escapes of a character adapted for the suspension and lowering of a person at a regulated speed.

One of the objects of the invention is to provide an improved device by which a weight may be suspended and lowered at a regulated speed through the medium of a drum and strap, the device being more particularly adapted for use as an escape from an elevation in case of fire.

A further object of the invention is to provide mechanism for automatic re-winding of the strap on removal of the weight.

A still further object of the invention is to provide an improved governor mechanism for braking the operation of the strap drum during lowering of the person.

The invention contemplates provision of a drum and a strap to be wound thereon, with spring means to be tensioned by the unwinding of the strap and automatically operable to re-wind the strap on the drum on removal of the object being lowered. There is further provided mechanism for braking the operation of the winding drum and regulating the descent of the person or object suspended therefrom.

To this end there is provided the novel mechanism as hereinafter more particularly described and claimed, reference being had to the accompanying drawings wherein like characters of reference indicate like parts throughout the several views and wherein:—

Fig. 1 is a detailed end view of a brake drum with governor mechanism.

Fig. 2 is a transverse sectional view of the brake drum and governor mechanism disclosed in Figure 1.

Fig. 3 is a side view in elevation of the preferred embodiment of the device assembled.

Fig. 4 is an end view of same.

Fig. 5 is a side view in elevation of a different form of fire escape that includes the principal features of the preferred form, certain parts of the device being illustrated sectioned.

Having reference to the drawings, there is provided a frame comprising substantially triangular end sections 1 and 2 which are inverted and provide upper horizontal bars and are connected by side bars 3, the whole forming a unitary structure within which the operating mechanism may be carried.

The end sections 1 and 2 include at their upper or horizontal portions ears 4 providing suitable eyes by which hook members 5 may be engaged for suspension of the device from a beam

or similar projecting member that would be attached to the building in respect to which the escape is to be used, a lateral projecting arm on which the hook members engage being more usually employed for this purpose, such an arm being common in the art.

Referring more particularly to Figures 1 to 4 inclusive, the end sections 1 and 2 of the frame structure carry a fixed shaft 6. The governor assembly includes a brake drum 40 with integral hub section 41 bored to be mounted on the shaft 6 fixed thereto by a set screw 6'. Within the drum 40, spaced from the hub section 41 by an annular enlargement 42 on the shaft 6, is a pinion 43 which is mounted to rotate on said shaft. Said pinion includes a hub section 44 to which is secured, or integrally cast, a series of radial arms 45. To each of said arms is secured a plate 46 providing ears to which are pivoted bell cranks 48—48, by pins 47.

The short arms of the bell cranks attach to shoes 49 mounted slidably on the radial arms 45, said shoes being disposed in braking relation to the inner circumferential wall of the brake drum 40. The long arms of the bell cranks attach to ears 50 on governor elements 51, said elements being in the form of spherical members as commonly used for such purposes. The elements 51 further include ears 52 to which connect springs 53 attaching to the hub sections 44, said springs being tensioned to normally hold the elements 51 with the brake shoes out of braking relation with the drum 40.

Rotation of the governor assembly through the action of centrifugal force causes the elements 51 to travel in a path spaced from the hub 44 relative to the rate of travel of the assembly. Through the operation of the bell cranks 48 this causes the shoes 49 to be moved into braking relation with the drum 40 and correspondingly reduce the rate of rotation of said drum.

On the shaft 6 is mounted a sleeve 7, said sleeve being free to rotate thereon. With the sleeve 7 is cast the hub 7' of a gear wheel 16. From the top connecting bars 3 is suspended a strap hanger 12 providing a bearing, as indicated at 13, in which is rotatable a shaft 14. On the shaft 14 is a gear wheel 15 meshing with the gear wheel 16. The shaft 14 has keyed on its other end a gear wheel 17 meshing with the pinion 43.

Fixed on the sleeve 7 is a drum 9 on which a strap 10 may be wound, the one end of the strap being fixed thereto. Said strap includes a hand grip.

Loose on the sleeve 7 is a casing 36 secured in fixed relation to the frame structure by brace members 37. Within said casing is mounted a spring 38 having one end secured to the casing and the other end attached to the sleeve 7 whereby rotation of the sleeve may serve to contract said spring. The unwinding of the strap 10 on drum 9, through rotation of the sleeve 7 imparts the necessary tension to spring 38 to reverse the movement of the sleeve when the weight is removed from the strap, and causes the strap to be re-wound on the drum ready for use.

In the operation of the device rotation of drum 9 by the unwinding operation of the strap 10, caused by weight of a person descending by means of the escape, imparts a corresponding rotation to the sleeve 7. This in turn through gear wheels 16 and 15, shaft 14, gear wheel 17, and pinion 43, imparts a rotary movement to the governor causing a braking action on the drum 40 by engagement of brake shoes 49, this action being designed to regulate the speed of descent to a predetermined maximum rate.

In Figure 5 is disclosed a variation of a governor for braking purposes. In this showing the pinion 18, which corresponds to pinion 43 previously described, forms an integral part of a plate 19. The plate 19 provides at intervals pairs of spaced ears 20, in each pair of which is pivoted an arm 21. The arm 21 carries a governor weight 22, each of said arms being connected by a spring 23 to a collar 24 mounted slidably on the shaft 6. The connections of said springs to the collar may be made adjustable for variation in operation of the governor.

Slidable on the shaft 6 is a plate 25, said plate including a hub portion 26 through which a pin 27 is passed, said pin being longitudinally slidable in suitable slots 28 in the shaft 6. To the pin 27 is secured one end of a rod 29.

On the shaft 6 is a brake plate 30 with hub section 31 carrying a transverse pin 32 longitudinally slidable in slots 33 in the shaft 6. The rod 29 connects to the pin 32 to provide for shifting the plate 30 on the shaft 6 in conformity with movement of the plate 25.

In opposing relation to the plate 30 is a plate 34 cast with the sleeve 7. The plate 30 is faced with suitable brake lining material as indicated at 35.

In the operation of this form of mechanism the unwinding operation of strap 10 imparts a rotary movement to plate 19, causing the divergence of the arms 21. The arms 21 include angular sections or feet 21' adapted to bear against the plate 25 and impart an endwise shifting to the rod 29. This in turn shifts the brake plate 30 to contact the plate 34 and brake the operation of the sleeve 7, serving to automatically regulate the speed of descent of a person suspended from the strap 10.

While we have shown and described specifically certain forms of the invention, it will be understood that this is for the purpose of illustration and that many modifications may be made in the various parts thereof, as well as in the relation of the invention in the art, without departing from the principles as embodied in the claims.

Having described and ascertained the nature of the invention and the manner in which the same is to be used, what we claim and desire to secure by Letters Patent is:-

1. A device of the character described including a frame, a shaft mounted in the frame, a sleeve free to rotate on the shaft, a drum fixed on the sleeve, a weight lowering strap attached to said drum to be wound thereon, a casing fixed in the frame loose on the sleeve, a coiled spring in the casing, said spring having one end secured to the casing and the other end attached to the sleeve, a governor mechanism mounted for rotation on the shaft, braking elements associated with the governor to be operated thereby, and a shaft and gearing forming a driving connection between the sleeve and governor mechanism.

2. A device of the character described including a frame, a shaft fixed in the frame, a sleeve free to rotate on the shaft, a drum carried by the sleeve, a weight lowering strap attached to the drum to be wound thereon, a governor mounted for rotation on the shaft, braking elements associated with the governor to be actuated thereby, a drum providing a braking surface for engagement by said elements, means forming a driving connection between the sleeve and governor, and spring means tensionable by the unwinding of the strap from the drum during lowering of a weight and automatically operable on release of the weight to rotate the drum to re-wind the strap thereon.

3. In a device of the character described including a frame with shaft mounted therein, and a drum rotatable on the shaft, said drum being adapted to have a weight lowering strap wound thereon, a governor for controlling the rotation of the drum, said governor comprising a brake drum fixed on the shaft, a hub in the brake drum rotatable on the shaft, a series of radial arms mounted on said hub, brake shoes slidable on said arms in braking relation to the circumferential wall of the brake drum, a governor mechanism carried by said arms, means forming an operative connection between the governor mechanism and brake shoes whereby said mechanism may operate to move said shoes into braking relation with said wall, and means forming a driving connection between the weight lowering drum and governor.

4. In a device of the character described including a frame with a shaft mounted therein and a drum on the shaft, said drum being adapted to have a weight lowering strap wound thereon, a brake drum fixed on the shaft, a combined governor and braking mechanism in the brake drum rotatable on the shaft, said mechanism including brake shoes frictionally engageable with the brake drum, a second shaft carried in the frame, means forming a driving connection between the weight carrying drum and second shaft, and means forming an operative connection between the second shaft and the governor and braking mechanism.
